CLAIM

The ornamental design for a charging data cable, as shown and described.

DESCRIPTION

FIG. 1 is a front perspective view of a charging data cable, showing my new design;

FIG. 2 is a front view thereof;

FIG. 3 is a rear view thereof;

FIG. 4 is a left side view thereof;

FIG. 5 is a right side view thereof;

FIG. 6 is an enlarged top view thereof;

FIG. 7 is an enlarged bottom view thereof; and,

FIG. 8 is a perspective view showing the charging data cable in a state.

The broken lines in the drawings illustrate the portions of the charging data cable, which form no part of the claimed design.

1 Claim, 8 Drawing Sheets
